UNITED STATES PATENT OFFICE.

LOUIS G. MILLER AND EDWARD C. LONG, OF WESTMONT BOROUGH, PENNSYLVANIA.

CAR-DOOR.

1,282,703.

Specification of Letters Patent. Patented Oct. 22, 1918.

Application filed May 4, 1918. Serial No. 232,668.

To all whom it may concern:

Be it known that we, LOUIS G. MILLER and EDWARD C. LONG, both citizens of the United States, and both residing in the borough of Westmont, in the county of Cambria and State of Pennsylvania, have invented certain new and useful Improvements in Car-Doors; and we do hereby declare the following to be a full, clear, and exact description of the invention, such as will enable others skilled in the art to which it appertains to make and use the same.

Our invention relates to drop doors for railroad freight cars and particularly to those of the hopper or hopper gondola types.

Our invention consists generally in constructing a door adapted to close or open a pair of hoppers, one on either side of the center sill of the car, the necessity for this arising particularly from the fact that the hopper cannot pass through the center sill, as the sill must be continuous throughout the car length and in order to provide the greatest number of openings, most hoppers are arranged in pairs, one on each side of the center sill. Heretofore these doors have been made separately for each hopper and have been connected together by means of what is known as door spreaders of various construction. As opposed to this, we make our door of one piece, one end being adapted to close or open one of the hoppers and the other end adapted to close or open the companion hopper. We preferably make the door narrower at its middle portion just below the center sill, as no closure is required at that place and we therefore save material, besides making the central portion of the door somewhat flexible so that it may twist slightly, if necessary, to insure tight closing against each of the hopper plates. We may also apply a truss structure to the door, adapted to stiffen it, particularly at its narrow portion and where the pull of the operating mechanism is applied, so that it may be drawn up tightly against the hopper without undue deflections, or the stiffening member may be made integral with the door.

Having thus given a general description of our invention, we will now, in order to make the matter more clear, refer to the accompanying two sheets of drawings in which like characters of reference indicate like parts:

Figure 1 is a vertical longitudinal sec-

tional elevation through a part of the lower portion of a car taken on the line I—I of Fig. 2;

Fig. 2 is a vertical transverse sectional elevation through the lower portion of the car taken on the line II—II of Fig. 1;

Fig. 3 is a top plan view of one style of our improved car door;

Fig. 4 is a side edge elevation of the door shown in Fig. 3;

Fig. 5 is a transverse sectional elevation taken on the line V—V of Fig. 3;

Fig. 6 is a top plan view of a modified style of car door;

Fig. 7 is a transverse sectional elevation taken on the line VII—VII of Fig. 6;

Fig. 8 is a side edge elevation of the door shown in Fig. 6;

Fig. 9 is a top plan view of another modified form of car door;

Fig. 10 is a transverse sectional elevation taken on the line X—X of Fig. 9;

Fig. 11 is a side edge elevation of the car door shown in Fig. 9;

Fig. 12 is a top plan view of another modified style of car door;

Fig. 13 is a transverse sectional elevation of the door taken on the line XIII—XIII of Fig. 12; and

Fig. 14 is a side edge elevation of the car door illustrated in Fig. 12.

Referring now to the characters of reference on the drawings:

1 indicates the car in general, 2 the side hopper sheets thereof, the lower edges of which are adapted to contact with the door and form closures together with similar hopper sheets extending on the other sides of the hopper to complete the closure. 3 is the central ridge of the car formed, as shown, of a plate bent angularly to cover the center sill and door operating mechanism, 4 indicates the door rigging in general, 5 the connecting links thereof, 6 are clevis bolts secured to the doors and connected with the links aforesaid. As illustrated in Figs. 1 to 5 inclusive, 7 indicates the car door in general, 8 an opening between the two portions thereof, the door being provided with an integral downwardly extending flange 9, extending around all the edges thereof, 10 is a spreader or truss bar shown as of channel section, bent downwardly at its intermediate portion and spaced apart from the door and provided with the bent strut plate 11 interposed between it and the door, the ends of

the spreader being secured or riveted to the door plate, as shown, and 12 is a flat reinforcing plate attached to the door, as illustrated.

- 5 As illustrated in Figs. 6 to 8 inclusive, 13 is the car door in general, 14 an opening between the two portions thereof, 15 is an integral flange on the forward end of the door which is preferably deeper at its intermediate portions and tapers thence to the ends of the door, this forward flange serving as a stiffening member for the door. This forward flange 15 has an inwardly bent portion 16 adapted to further strengthen and stiffen it. The rear integral flanges of the door are 17 and it is also provided with integral side flanges, as shown, in fact, the entire door is provided with an integral continuous flange extending downwardly from all the edges thereof, the front flange being deeper and tapering as above described. 18 is the integral flanged edge of the door at its narrowest portion adjacent to the opening 14, 19 is a pan-shaped brace either formed of pressed plates or a casting secured to the door, as illustrated, and provided with an opening to receive the clevis bolt 20, which is secured thereto, as illustrated, for the purpose of attaching to the door operating mechanism.
- 30 Referring now to Figs. 9 to 11 inclusive, 21 indicates another slightly modified form of door in general, provided with two end portions and a space or opening 22 between the same, 23 is the front flange portion formed integral with the door, projecting downwardly therefrom and of less depth at the ends than at the central portion, being provided with an integral flanged edge 24 which projects outwardly, as illustrated, to further stiffen the door, in addition to which the reinforcing angle 25 is secured to the intermediate portion thereof, as illustrated. This door is also provided with an integral flange extending around all the edges thereof, that at the narrowest portion being 26 and the rear flange 27. A brace 28, which may be either formed of pressed plates or a casting, is secured to the door, as illustrated, and provided with an opening 50 to receive the clevis bolt 29, which is adapted to be secured to the door operating mechanism.

Referring now to Figs. 12 to 14 inclusive, another slightly modified form of door is indicated generally as 30, 31 is the opening or space between the two portions thereof, the integral rear and end flanges are 32, the integral deeper and tapering front flange edge is 33, provided with forwardly projecting integral portion 34, this door being provided with a pair of flanged stiffeners 35 and 36, the latter being shorter than the former, both secured to the door plate and provided with a space between them at their intermediate portions, adapted to receive the clevis

bolt 37, the nut of which rests against the washer plate 38.

It will be seen from the foregoing that we provide a door made in one piece adapted to close a pair of twin hoppers, one on either side of the center sill of the car or otherwise and all margins of the door are provided with downwardly extending flanges formed integrally therewith and the door is also provided with connections to the operating mechanism. These doors are all provided with hinges and hinge plates, as illustrated generally in Fig. 1, the holes for the connections being indicated on the various doors.

Although we have shown and described our improvements in considerable detail, we do not wish to be limited to the exact and specific details shown and described, but may use such substitutions, modifications, or equivalents thereof, as are embraced within the scope of our invention, or as pointed out in the claims.

Having thus described our invention, what we claim and desire to secure by Letters Patent is:—

- 90 1. A car drop door comprising a metal plate provided with an integral downwardly extending flange on its edges, the intermediate portion being narrower than the end portions.
- 95 2. A car drop door having its intermediate portion narrower than the end portions, comprising a metal plate provided with an integral downwardly extending marginal flange on all edges thereof, the flange on the forward edge adjacent to the door operating mechanism being deeper.
- 100 3. A car drop door having its intermediate portion narrower than the end portions, comprising a metal plate provided with an integral downwardly extending marginal flange on all edges thereof, the flange on the forward edge adjacent to the door operating mechanism being deeper at the center and tapering thence toward the ends.
- 105 4. A car drop door comprising a pair of doors integrally united by a narrow portion and provided with an integral downwardly extending marginal flange on all edges thereof.
- 110 115 5. A car drop door comprising a metal plate of substantially rectangular outline, the intermediate portion of which is narrower than the end portions, integral downwardly extending marginal flanges on all edges thereof, a longitudinal stiffening member secured near the front edge thereof, and means for attaching the door operating mechanism thereto.
- 120 6. A car drop door comprising an integral metal plate narrower at the center than at its end portions, a marginal flange on all edges thereof, a flanged stiffening member secured to the door plate near the outer edge thereof and adapted to reinforce the
- 125 130

narrow central portion of the door, and provided with a clevis bolt secured thereto for attachment to the door operating mechanism.

5 7. A car drop door comprising a metal plate composed of a pair of substantially rectangular end portions, an integral narrow portion connecting the same, integral downwardly extending marginal flanges on 10 all edges thereof, the forward flange being deeper than the others and provided with ends tapering gradually to substantially the same depth.

8. A car drop door comprising a metal 15 plate, the central portion of which is nar-

rower than the end portions, integral marginal flanges extending downwardly from all the edges thereof, the forward flange being deeper than the others and tapering from its central portion toward the 20 door ends, a flanged reinforcement attached to the door plate and provided with an opening therethrough, adapted to receive a clevis bolt for attachment to the door operating mechanism.

25 In witness whereof we hereunto affix our signatures.

LOUIS G. MILLER.
EDWARD C. LONG.
